AUTOMATIC HOOD GUARD

William D. Drummond, Cliffside, N. J.

Application July 2, 1934, Serial No. 733,390

9 Claims. (Cl. 143—159)

My present invention relates to the art of accident prevention, and has particular reference to hood guards for use with circular saws.

The hood guards heretofore used for circular saws consist of a hood or the like which rises when the work is inserted, but which affords no protection for the fingers of the operator, as the saw teeth are free to be contacted by the operator both at the point where the saw emerges from the table and at the point where the saw leaves the table. It is the principal object of my invention to provide an automatic hood guard which will fully protect the fingers of the operator at all times, without interfering with the normal operation of the saw.

The hood guards heretofore used have also been disadvantageous in that no means have been provided for positively eliminating kick-back, as the kick-back has two causes, namely, pinching of the work after it leaves the saw, and direct backward thrust of the saw. It is a further object of my invention to provide automatic means for eliminating any kick-back, whether due to pinching of the work or to engagement of the saw with the work.

A further difficulty found in hood guards, particularly of the stationary type, has resided in the inability of the hood guard to move or yield backwards. It is therefore an additional object of my invention to provide an automatic hood guard arrangement which has a certain amount of backward yield or travel under unusual circumstances, but does not lose its protective features when so moved.

I have further found it desirable to provide a novel locking arrangement whereby the hood guard may be instantly attached or detached from its protective position, the locking arrangement being positive in action and holding securely against accidental release.

With the above and other objects and advantageous features in view, my invention consists of a novel arrangement of parts more fully disclosed in the detailed description following, in conjunction with the following drawings, and more specifically defined in the claims appended thereto.

The accompanying drawings illustrate a preferred embodiment of my invention, like characters of reference indicating like parts throughout the views;

Fig. 1 is a side elevation showing a conventional saw frame with the novel guard in operative position;

Fig. 2 is an incomplete fragmentary section thereof on the line 2—2 of Fig. 1;

Fig. 3 is an enlarged plan view of the guard, the novel slide fingers being shown in section;

Fig. 4 is a side elevation thereof on the line 4—4 of Fig. 3;

Fig. 5 is a detailed elevation of the novel spreader;

Fig. 6 is a detailed view showing the novel locking attachment, and

Figs. 7, 8, and 9 are side elevations illustrating the operation of the novel guard parts during a sawing operation.

It has been found advisable to provide an automatic hood guard which effectively prevents contact of the operator's fingers with the saw teeth through the entire sawing operation, the parts being so arranged that the saw teeth are not uncovered or open at any time. I have therefore devised a novel automatic hood guard which is quickly attached or detached, and which has members which prevent engagement of the operator's fingers with the saw teeth, while the work is entering the saw, during the sawing operation, and while leaving the saw. Moreover, I have provided positive means for preventing kick-back of the work by utilizing a spreader for keeping the bifurcated sawed parts apart, and dogs which positively engage the work so as to prevent rearward movement thereof.

A preferred embodiment of my invention is illustrated in the drawings, in which the frame work 10 has the usual table 11, a rock shaft 12 being suitably journaled in the frame work and having actuating mechanism of standard type. A bearing support 13 is keyed to the rock shaft 12 and has spaced bearings 14, see Fig. 2, for the arbor 15 which carries the driving pulley 16, a belt 17 of standard type passing around guide rolls 18 and 19 and supplying power for driving the arbor 15, thus rotating the saw 20 which is keyed thereto. The arbor has the usual standard mechanism for adjustment and for locking the saw on the spindle, including ball bearing races, such as for example shown in my previous Patent No. 1,711,490, and has a collar 21 mounted thereon for receiving the hub 22 of a pivot arm 23, see Fig. 5, which has its end engageable with the lower surface of the table, a tension spring 24 connecting this arm to a similar arm 25 also having a hub 26 rotatably mounted on the collar, the arm 25 having an arcuate spreader 27 secured at its free end which normally projects above the table so as to overhang the rear end of the saw a short distance away from the saw

teeth. The spreader is of the same width as the saw and in alignment therewith, and functions to maintain the cut portions separated, thus effectively preventing pinching of the work and any kickback resulting therefrom.

The novel automatic hood guard is releasably mounted at the upper end of the spreader, the spreader having a plurality of openings 28 for receiving a locking pin, as hereinafter described.

10 The automatic hood guard consists of two parallel plates 29, 30 having cylindrical spacing bosses 31 near their forward ends secured by a connecting screw 31a, and having near their rear ends vertically elongated spacing blocks 32 integral 15 with the plates and connected with each other by a horizontal plate 32a secured by screws 32b. A cam finger 33 is mounted at the front of each plate by means of a hinge bolt 34, the ends of the hinge bolts threadedly engaging suitable 20 openings in the side plates. The cam finger 33 is normally adapted to rest on the face of the table and has a tip 35 provided with a cam edge 36, which is engageable with a pin 37 secured to a slide finger 38, the upper end of the slide 25 finger contacting with a cross bar 39 integral with a second slide finger 40, both fingers being housed for vertical sliding movement in a bracket 41 fastened to the side of the plate, the bracket having a vertical internal shoulder 42 intermediate 30 its width forming resultant vertical channels 43 to guide the movement of the slide fingers, the latter being movable synchronously in an upward direction but capable of successive movement downwardly under the influence of 35 gravity, and also having retaining studs 41a which seat in vertical grooves 42a in the slide fingers to lock the slide fingers in place.

The rear end of each plate is similarly equipped with a cam finger 44 which is also hinged to 40 the side plate by means of a hinge bolt 45, and has a tip 46 normally resting on the face of the table, with an upper cam edge 47 engageable with a pin 48 on a rear slide finger 49, the upper edge of the slide finger 49 contacting with a cross 45 bar 50 attached to a second slide finger 51, both slide fingers being housed for vertical movement in a retaining bracket 52 secured to the side plate, the retaining bracket having a vertical internal shoulder 52a which forms channels 53 50 for receiving the slide fingers, and retaining studs which cooperate with vertical channels in the slide fingers, as for the front slide fingers, to lock the slide fingers in the bracket channels. The table engaging ends of the cams and slide 55 fingers are preferably rounded.

Locking mechanism for releasably attaching the automatic hood guard to the spreader is positioned intermediate the side plates, and consists of two arms 55, 56 which have hubs at their lower ends pivotally mounted on a cross pin 57 secured to the two plates, the arm 55 having a pin 58 at the end thereof and the arm 56 having a slot 59 at the end thereof, the pin 58 being adapted to be inserted through and extend beyond one of the openings 28, and the slot 59 being adapted to fit over the end of the pin. The arm 56 has two spacer supports 60, 61 through which a manually slidable rod 62 extends as illustrated, a compression spring 63 being positioned intermediate the support flanges to cooperate with a cross pin 64 extending through the rod 62 so as to normally urge the locking rod to extended position, the arm 55 having a flange 65 provided with an opening 66 for receiving the extended 70 end of the locking rod, whereby the positioning 15

of the end of the locking rod in the opening 66 releasably locks the two arms 55 and 56 in parallel arrangement to thus retain the pin 58 in the opening 28. Two dogs 67 and 68 are pivotally mounted on the ends of the arms 55 and 56, and are balanced so as to have their maximum weight below the pivot point, the lower ends of the dogs being cut so as to present sharp points forwardly for digging into the work as herein- 10 after explained.

The operation of the automatic saw guard may now be explained, with particular reference to Figs. 7, 8, and 9. As the work is advanced towards the saw, the front edge of the work engages the front cam fingers, lifting the cam fingers 15 and the front slide fingers as a unit, the cam and slide fingers functioning as a fence prior to engagements of the work with the cam fingers so as to prevent any movement of the operator's fingers towards the front portion of the saw. As the work advances during the sawing operation, the cam and slide fingers ride on the upper surface of the work, the hood moving upwardly on the lock pin if the work is high. As the work advances further, the points of the dogs ride on the surface of the work and are thus placed in gripping position so as to prevent any rearward movement of the work; the rear cam fingers are engaged and move upward, simultaneously lifting the rear slide fingers, the rear cam and slide 25 fingers normally functioning as a fence to prevent any insertion of the fingers of the operator towards the rear saw teeth. As the work advances further, the front cam fingers and the front slide fingers are successively released and drop to the 30 table, thus protecting the fingers of the operator; the rear cam and slide fingers are then successively released and drop to the table so as to prevent any contact of the operator's fingers with the rear end of the saw. Although the front cam 40 and slide fingers are successively released, it has been found preferable to so shape the rear cam finger that the rear cam and the first slide finger are simultaneously released, the second rear slide finger then dropping.

While I have described and illustrated a preferred embodiment of my invention, changes in the size, in the relative proportion of the parts, in their arrangement, and in the material used for the parts, may be made to suit the requirements for different saw mechanisms, within the spirit and the scope of the invention as defined in the appended claims.

I claim:

1. In a saw guard, side members positioned to receive a saw therebetween, slide elements mounted for sliding movement in said side members, and means engageable by the work for lifting said slide elements in unison, said slide elements being successively released upon passage of the work past the slide elements.

2. In a saw guard, side members positioned to receive a saw therebetween, slide elements mounted for sliding movement in said side members, and means engageable by the work for lifting said slide elements in unison, said slide elements being successively released to fall by their own weight upon passage of the work past the slide elements.

3. In a saw guard, a hood comprising side members positioned to receive a saw therebetween, finger guards including a plurality of slide elements mounted for sliding movement in the side members, means responsive to forward movement of the work to simultaneously lift said slide ele- 70 75

ments, said slide elements being successively returned to their initial position upon passage of the work therebeyond.

4. In a saw guard, a hood comprising side members positioned to receive a saw therebetween, finger guards including a plurality of slide elements mounted for sliding movement in the side members at each end thereof, means responsive to forward movement of the work to simultaneously lift said slide elements at said ends, said slide elements being successively returned to their initial position upon passage of the work therebeyond.

5. In a saw guard, a hood having side members positioned to receive a saw therebetween, a group of slide elements at each end of the side members, cam elements pivotally mounted at each end of the side members each cooperating with a group of slide elements, and adapted to be lifted by contact of the work therewith, and means for moving each group of slide elements upon lifting of their associated cam element, said slide elements being successively returned to their initial position upon passage of the work therebeyond.

6. In a saw guard, a hood having side members positioned to receive a saw therebetween, a group of slide elements at each end of the side members, cam elements pivotally mounted at each end of the side members each cooperating with a group of slide elements, and adapted to be lifted by contact of the work therewith, and means whereby lifting of the associated cam element moves one slide element to in turn move a sec-

ond slide element, said slide elements being successively returned to their initial position upon passage of the work therebeyond.

7. In combination, a hood guard support having an opening, a hood guard, releasable locking means on said hood guard comprising two pivoted elements, a laterally extending pin on one element, a slot on the other element adapted to seat in said support opening, and means for releasably locking said elements with said pin extending into said slot.

8. In combination, a hood guard support having an opening, a hood guard, releasable locking means on said hood guard comprising two pivoted elements, a laterally extending pin on one element, a slot on the other element adapted to seat in said support opening, and means for releasably locking said elements with said pin extending into said slot, said means comprising a catch member on one element and a latch member releasably engageable therewith on the other element.

9. In combination, a hood guard support having an opening, a hood guard, releasable locking means on said hood guard comprising two pivoted elements, a laterally extending pin on one element, a slot on the other element adapted to seat in said support opening, and means for releasably locking said elements with said pin extending into said slot, said means comprising an opening in one member, and a spring pressed bar releasably engageable therewith.

WILLIAM D. DRUMMOND.
